REFRIGERATOR

Frank D. Peltier, Jenkintown, Pa., assignor, by
mesne assignments, to Philco Corporation,
Philadelphia, Pa., a corporation of Pennsyl-
vania

Application November 30, 1944, Serial No. 565,846

10 Claims. (Cl. 62—2)

1

This invention relates to refrigerators and while not specifically so limited, is more particularly adapted for use with refrigerators of the horizontal top-access type.

An important object of the invention is to provide a refrigerator of a character adapted for operation, selectively, as either a household refrigerator operating at conventional temperatures, or as a low temperature freezer chest, as desired by the user.

Another object of the invention is the provision of such a refrigerator wherein selection between different temperature conditions is accomplished in an automatic manner, during the process of making certain structural rearrangements when changing from one operating condition to the other.

To this general end the invention, in one aspect, contemplates the utilization of a movable member adapted for differing positional adjustment in accordance with the desired type of operation and which, by virtue of said positional adjustment effects corresponding variations in the temperature condition within the storage space.

The invention extends further to certain novel structural details and arrangements hereinafter described and illustrated in the accompanying drawings, in which:

Fig. 1 is a longitudinal vertical sectional view of a horizontal top-access refrigerator embodying the invention and taken along line I—I, Fig. 2;

Fig. 2 is a fragmentary transverse vertical sectional view of the refrigerator, taken along the line II—II, Fig. 1; and

Fig. 3 is a diagrammatic representation of the temperature control apparatus.

Referring more particularly to the details of the drawing, wherein is illustrated one embodiment of the invention, the numeral 10 designates a horizontal top-access refrigerator comprising a cabinet 11 having a closure lid or door 12. The cabinet 11 includes an outer shell 13 and an inner liner or tank 14 supported in spaced relation within said shell. The usual breaker strip 16 of low thermal conductivity is provided between the inner rim 17 of the shell and the rim 18 of the liner, said breaker strip being provided with a gasket portion 19. As shown, this supporting breaker strip is of the general type disclosed and claimed in the pending application of Theodore W. Rundell, Serial No. 516,475, filed December 31, 1943, now Patent No. 2,426,535, granted August 26, 1947.

Insulating material 20 fills the space between the outer shell 13 and the sides 21 and 21a of the inner liner 14, while additional insulating material 22 is supported beneath the bottom wall 23 of said liner by a horizontal partition or pan

2

24, the edges of which are secured to outer shell 13, as by welding or other suitable means. The pan forms the top wall of a compartment 25 within which is housed both the motor-compressor unit 26, which may be of the hermetically sealed type, and a refrigerant condenser 29.

The door, which may be attached, as by hinges (not shown) to the shell 13, is of the plug type and is formed with a projecting flange portion 30 which seats upon the upper periphery 31 of shell 13 and cooperates with gasket 19 to establish an air-tight and leak-proof joint between the door and the cabinet walls.

Positioned within one end portion of the inner liner adjacent the left transverse side wall 21 (Fig. 1) is the main body portion of an evaporator 33, which body portion is preferably formed in the conventional U-shaped configuration. The evaporator also includes several convolutions of tubing 34 attached in any convenient manner to the right transverse side wall 21 of the liner, as viewed in Fig. 1, which tubing is connected to the evaporator by an extension 35 thereof which extends through the walls of the liner and the insulation 20. The evaporator, including the tubing 34 and 35, is connected in series flow circuit with the compressor 26 and condenser 29, the usual capillary tube 37 serving to conduct liquid refrigerant from the condenser to the evaporator, and a suction conduit 38 being provided, through which gaseous refrigerant passes from the evaporator back to the compressor. As will be apparent from the drawing, the compressed refrigerant flows from the compressor to the condenser through a conduit 36.

In the embodiment illustrated, the U-shaped body portion of the evaporator divides the inner liner into two compartments 39 and 40. The compartment 39 provides the main lower temperature zone, and is defined by the opposite walls 41 of the evaporator and portions of the opposed longitudinal side walls 21a of the liner. The compartment 40 provides the main food storage zone and is defined by one wall 41 of the evaporator, the right transverse side-wall 21 of inner liner 14 (as viewed in Fig. 1) and portions of the opposed longitudinal side-walls 21a of the liner.

In particular accordance with the present invention a pair of baffles 50 and 51 are pivotally mounted upon the longitudinal side walls 21a of the liner along horizontal axes, as indicated at 52—52, and as best seen in Fig. 2. These baffles may be moved about their pivotal axes between two terminal positions including the vertical position shown in full lines, in which each baffle is releasably held by a latching member 53, and a horizontal position overlying the floor 60 of the liner, said latter position being indicated

in broken lines at 54. Since, as will be brought out more fully hereinafter, a primary purpose of the baffles is to reduce direct contact between the compartment air and the evaporator surfaces under one condition of operation, said baffle may, if desired, be of metallic construction.

However, it will be understood that the baffles may also be of such a material as to provide a considerable impedance to the flow of heat therethrough, if desired.

Each baffle is provided with a pair of opposed inwardly extending ear portions 55 and 56, located on the opposed side edges substantially intermediate the ends thereof and to which is pivotally mounted a shelf 57. These shelves are adapted to assume a horizontal position substantially at right angles to said baffles, when the baffles are in their vertical position, and to fold into a horizontal position parallel to said baffles and the floor 23 of the liner, when the baffles are lowered to the position adjacent the liner floor. To hold the shelves in the horizontal position, as illustrated in full lines on Fig. 1, each baffle is provided with support means comprising a pair of short supporting projections 58 (Fig. 2) which extend beneath the shelf when it is in the raised extended position illustrated. It should be understood that these supports do not project to an extent sufficient to interfere with folding of the shelves when the baffles are lowered to the position illustrated by broken lines 54.

As clearly illustrated in Fig. 2, the pivotal mounting of the baffles is provided by a pair of opposed pivot pins 60 journaled in the longitudinal side walls 21a of the liner. It will be noted that one of the pivot pins upon which baffle 50 is mounted extends through the liner into operative connection with the actuating shaft of a temperature control 62 which may be attached to the liner in any suitable manner, as by the angular support bracket illustrated at 63.

The temperature control may be of any desired type, an exemplary diagrammatic showing being illustrated in Fig. 3. As shown, this control includes a bellows-type power element 65 (Fig. 3) having a feeler bulb 66 attached to the evaporator in any convenient manner, as at 67, and connected in open communication with the bellows by a tube 68. The bellows system is charged with a suitable volatile liquid which expands when the evaporator temperature rises above a predetermined value, thereby exerting pressure against a spring-pressed toggle-switch actuating arm 68. The pressure so exerted moves the arm 68, against the pressure of spring 69, to the left, as illustrated in Fig. 3, to snap a movable switch arm 70 into contact with the stationary contact element 71, thus closing the toggle switch.

The switch is connected in circuit with the compressor motor, indicated at 72 and a suitable power source represented at 73, as by the leads 74. Thus, when the switch is closed, the system operates to lower the temperature of the evaporator to the desired value, upon the attainment of which the pressure in the bellows decreases to an extent permitting spring 69 to move the arm 68 in the reverse direction, thereby breaking the circuit.

It will be understood that by adjusting the tension of spring 69 the operating cycle, or the time during which switch 72 remains closed (and therefore the box temperature) may be increased or decreased. To this end the spring is backed by an adjustable tensioning screw-member 75, having a control shaft 76. This shaft would nor-

mally be supplied with a control knob for manual operation only, but, in particular accordance with the instant invention, the shaft 76 is operatively connected to the pivot pin 60 of baffle 50, as at 77.

By turning the shaft 76 of this tensioning device, in one direction, as by moving baffle 50 from one terminal position to another, for example counter-clockwise as viewed in Fig. 1, the resistance the spring exerts against movement of switch arm 68 is increased and the period during which the switch remains closed is correspondingly decreased, since a greater bellows pressure (corresponding to a higher temperature condition) is required to overcome the pressure of the spring 69.

Conversely when the shaft is turned in a clockwise direction, as by lowering the baffle, the spring pressure is decreased and the operating cycle of the refrigerating system is correspondingly increased, to lower the temperature to that suitable for freezer chest uses.

Due to limitations inherent in refrigerating systems, the temperature range over which a system is capable of operating efficiently is comparatively short and, therefore, by causing the baffles 50 and 51 to shield the air in compartment 40 against direct contact with the walls of the evaporator portions, in addition to the direct temperature adjustment which they effect, it is possible to operate the refrigerator at a higher temperature than would be the case if reliance were placed upon adjustment of the temperature control alone. For this reason, the invention makes possible the maintenance of the low temperatures necessary to safely store frozen foods, while still providing freedom for operation as a conventional household refrigerator, without the sacrifice of efficiency.

In operation of the refrigerator, when it is desired to operate at lower temperatures, it is only necessary to fold up the shelves and lower the baffles to their position across the bottom wall of the liner. As will now be understood, this movement rotates the temperature control in a manner to permit the refrigerating system to lower the operating temperature, and at the same time exposes the evaporator to the air in the compartment. On the other hand, when it is desired to operate the refrigerator at higher temperatures, the shelves are erected by raising the baffles, thereby providing additional area upon which foodstuffs may be placed. Raising the baffles in turn, rotates the temperature control in a manner to permit evaporator temperature to rise to the desired degree. Conveniently, and as described hereinabove, the higher and lower temperature conditions may be of such a value as to enable operation as either a conventional refrigerator or as a freezer chest, respectively.

In conclusion, it is evident from the foregoing that raising or lowering of the shelves, by suitably positioning the baffles, results automatically in temperature adjustments in correspondence with the desired mode of refrigerator operation. Since shelves are desirable during operation at the higher temperatures, when frequent access is had to the contents of the refrigerator, and undesirable under cold temperature storage conditions, the simplicity and effectiveness of the device of the present invention will be apparent.

I claim:

1. In a refrigerator including a space adapted for use under differing conditions of operation selectively, means for cooling said space, adjusta-

ble means for controlling the operation of said cooling means to vary the temperature within said space, and a movable baffle within said space and adapted for differing positional adjustment in correspondence with the operating condition selected, said baffle further being so operatively associated with said controlling means as to vary the adjustment of said controlling means in accordance with the positional adjustment of the baffle.

2. In a refrigerator including a space adapted for use under differing conditions of operation selectively, means for cooling said space, adjustable means for controlling the operation of said cooling means to vary the temperature within said space, a baffle within said space adapted for differing positional adjustment in correspondence with the operating condition selected, and means so interconnecting said baffle and said controlling means as to effect variations in the adjustment of the controlling means in accordance with the position of said baffle.

3. In a refrigerator including a space adapted for use either at conventional temperatures or at relatively low storage temperatures selectively, means for cooling said space, adjustable means adapted to control the operation of said cooling means to maintain said space at the selected one of the aforesaid temperatures, a baffle within said space adapted for movement to an operative position when the refrigerator is to be operated at conventional temperatures or to a rest position upon selection of storage temperature operation, and means interconnecting said baffle and said controlling means and effective to adjust said controlling means in correspondence with the baffle position selected.

4. A construction in accordance with claim 3, wherein said cooling means is within said space and said baffle is effective in said operative position to substantially prevent contact between said cooling means and the air within said space.

5. In a refrigerator including a space to be cooled to different temperatures selectively, means for cooling said space, at least a substantial portion of said means being positioned therewithin, means for controlling the temperature of said cooling means, and movable means for regulating the contact of air within said space with said cooling means, said movable means further being so associated with said temperature control means that movements of said movable means effect variations in the temperature of said cooling means.

6. In a refrigerator including a space to be cooled to different temperatures selectively, means for cooling said space, said means including an evaporator at least a portion of which is positioned within said space, temperature control means including an actuating shaft, a pivotally mounted baffle adapted to regulate contact between the air within said space and said evaporator portion, said baffle further being operatively connected to the actuating shaft of said temperature control whereby pivotal movements of said baffle effect variations in the temperature of said cooling means.

7. In a refrigerator including a compartment adapted for use under different conditions of operation selectively, means for cooling said compartment, baffle means adapted for different positional adjustment with respect to said cooling means in correspondence with the operating condition selected, said baffle means being effec-

tive to regulate the degree of contact between compartment air and said cooling means in accordance with the positional adjustment of said baffle means whereby to vary the cooling effect of said cooling means, and a shelf within said compartment movable between operative article-supporting and rest positions, said shelf and said baffle means being so operatively interconnected that said shelf is selectively disposable in said positions in accordance with the positional adjustment of the baffle.

8. In a refrigerator including a compartment adapted for use under different conditions of operation selectively, means for cooling said compartment, baffle means within said compartment adapted for different positional adjustment with respect to said cooling means in correspondence with the operating condition selected, said baffle means being effective to regulate the degree of contact between compartment air and said cooling means in accordance with the positional adjustment of said baffle means whereby to vary the cooling effect of said cooling means, and a shelf within said compartment and pivotally supported upon said baffle means for movement to article-supporting and rest positions, the pivotal support for said shelf being such that said shelf is moved to a rest position when said baffle means is in one position of adjustment and is disposed for movement to an article-supporting position when said baffle means is in another position of adjustment.

9. In a refrigerator including a compartment adapted for use either at conventional refrigeration temperatures or at relatively low storage temperatures selectively, means for cooling said compartment, baffle means within said compartment and adapted for movement to either of two terminal positions in accordance with the selected temperature condition, said baffle means being effective to reduce the degree of contact between compartment air and said cooling means when said baffle means is moved to one of said terminal positions, said baffle means permitting free access of compartment air to said cooling means when the baffle means is in the other of said terminal positions, and a shelf movable between operative article-supporting and rest positions, said shelf and said baffle means being so operatively interconnected that said shelf is moved to its rest position in response to movement of said baffle means to said other terminal position.

10. In a refrigerator including a compartment adapted for use under different conditions of operation selectively, means for cooling said compartment, adjustable means for controlling the operation of said cooling means to vary the temperature within said compartment, and a shelf within said compartment and selectively disposable in different positions in accordance with the operating condition selected, said shelf being linked to said controlling means and effective to vary the adjustment of the latter in response to variations in the position of said shelf.
